ATTORNEYS

UNITED STATES PATENT OFFICE.

HARRY P. MCINTIRE, OF COLORADO SPRINGS, COLORADO.

CONCENTRATOR.

1,116,092.

Specification of Letters Patent.

Patented Nov. 3, 1914.

Application filed May 7, 1913. Serial No. 768,010.

To all whom it may concern:

Be it known that I, HARRY P. MCINTIRE, a citizen of the United States, and a resident of Colorado Springs, in the county of El Paso and State of Colorado, of the United States of America, have made a new and useful Improvement in Concentrators, of which the following is a specification.

My invention relates to improvements in a device for concentrating ores, and it consists in the combinations, constructions and arrangements herein described and claimed.

An object of my invention is to provide a device for concentrating ores which is cheap to manufacture and in which economy of power is effected.

A further object of my invention is to provide a device in which a great economy of water is effected, and having a large capacity in proportion to its size.

The further object of my invention is to provide a device which is of a portable nature.

Other objects of the invention will appear in the following specification and the novel features of the device will be particularly set out in the appending claim.

My invention is illustrated in the accompanying drawings forming a part of this application in which—

Figure 1 is a section through the device. Fig. 2 is a plan view of the device. Fig. 3 is a detail view showing a portion of the face of the concentrator belt. Fig. 4 is a view similar to Fig. 3, showing a modified form of belt. Fig. 5 is a view similar to Figs. 3 and 4 of another modified form of belt. Fig. 6 is an enlarged section along the line 6—6 of Fig. 3. Fig. 7 is an enlarged section along the line 7—7 of Fig. 4. Fig. 8 is an enlarged section along the line 8—8 of Fig. 5, and Fig. 9 is a detail view showing the means for vibrating the belt carrier.

In carrying out my invention I provide a tank 1 of any suitable construction, having bearings 2 upon which is mounted a main driving shaft 3. One end of the driving shaft is provided with a driving pulley 4. Mounted upon the shaft 4 is a yoke 5, a friction wheel 6 and an eccentric 7 (see Fig. 2). Carried by the yoke 5 is a shaft 8 bearing a friction disk 9 which is arranged to be engaged by the friction wheel 6. The shaft 8 is really in two sections being provided with a universal joint 8'. This shaft, as will be seen from Fig. 1, is normally in-

clined and toward its lower end is provided with a worm 9. The shaft 8 has a slot 8^x which permits the worm to slide longitudinally of the shaft.

Mounted upon supports, such as those shown at 10, within the tank, is a belt carrier or frame 11. This frame bears at one end a gear 12 arranged to be engaged by the worm 9. The gear is connected with a drum 13, (see Fig. 1) over which an endless belt 14 (see Fig. 2) is arranged to travel. The opposite end of the carrier 11 is provided with a similar drum or roller 13^x for supporting the belt. The frame 11 is arranged to be vibrated in a direction at right angles to the travel of the belt by means of a device which is illustrated in Figs. 1 and 9. The eccentric 7 is connected by means of a rod 15 with a toggle joint 16, one end of which is fastened to the side of the tank 1, the other end being fastened to one of the trunnions 17 of the belt carrier.

At the lower end of the belt carrier frame is a trough 18 for receiving the tailings, while directly underneath the roller 13, shown in dotted lines in Figs. 1 and 2, is a hopper or receptacle 1^x formed of a portion of the bottom of the tank 1.

A hopper 19 communicates with a feed device (not shown) which may be of any suitable type and which is driven by means of a pulley 20 operated by a belt 21 which passes over a pulley on the drive shaft 3^x. A chute or spout 22 extends downwardly toward the belt and terminates just above the latter as shown in Fig. 1.

The belt 14 is preferably provided with baffles or riffles. I may use a belt like that shown in Fig. 3 or one like that shown in Fig. 4 or Fig. 5. In Fig. 3 the belt 14 is provided with a series of curved riffles 14^a. The belt shown in Fig. 4 is provided with a series of central riffles 14^b, with corrugations 14^c formed in the face of the belt, these corrugations being disposed at an angle of approximately 10° and sloping from the sides of the belt toward the central row of riffles.

In Fig. 5 I have shown a belt having a row of riffles 14^d at one edge with corrugations 14^e formed in the belt and sloping from the opposite edge toward the riffles 14^d.

From the foregoing description of the various parts of the device the operation thereof may be readily understood. The tank 1 is filled with water up to the line α α shown in Fig. 1. The ore is fed in through

the hopper 19 and passes down through the chute 22 upon the belt. The revolution of the shaft 3 drives the disk 9 through the medium of the friction wheel 6. This turns 5 the shaft 8 which through the medium of the worm 9 and gear 12 drives the upper drum 13 thereby causing the travel of the belt 14 over the drums 13 and 13'. The ore falling on the belt is carried upwardly. The motion imparted to the carrier 11 by the toggle 10 joint arrangement described tends to agitate the ore so that the lighter particles pass down the inclined belt and are deposited in the trough 18 from which they may be deposited 15 in the bottom of the tank. The heavier and more valuable portions of the ore are carried upwardly and are dumped into the receptacle 1* from which they may be removed in any suitable manner.

20 The belt carrier may be tilted at an angle greater or less than that shown, the angle depending upon the ore to be treated. In order to accommodate itself to the position of the gear wheel 12 carried at the end of 25 the carrier 11, the shaft 8 is slotted at 8' as stated before so that the worm wheel 9 may slide longitudinally thereof. The universal joint 8' permits the motion to be transmitted to the lower portion of the shaft 8 even 30 though the upper part may not be in exact alignment.

When the form of belt shown in Fig. 3 is used the ore is fed the full width of the belt. In the form shown in Fig. 4 the ore is fed on 35 the outer edge of each side, while in form shown in Fig. 5 the ore is fed on the edge opposite the curved riffles.

It will be observed that the operation of 40 concentrating the ore is carried out entirely under water, the ore being fed at least two feet below the surface of the water directly upon the surface of the belt, thereby eliminating slime throughout the tank. The

separation under water is effected by the buoyancy of the lighter particles and the 45 heavier weight of the more valuable portions. The agitation of the belt carrier permits the lighter portions to pass downwardly while the heavier portions are caught by the riffles and are carried upwardly. 50

From the construction above described, it will be apparent that the transverse movement of the belt carrier is such as to maintain the working part of the belt, *i. e.*, that part upon which the ore is fed, in a plane 55 parallel with itself. Unless this is done there is danger of the heavier particles being thrown over the riffles and passing down the belt instead of being carried parallel. I have found that it is necessary to impart a 60 vibratory movement of the belt in its own plane in order to successfully accomplish a satisfactory separation.

I claim:

In a device for concentrating ores, a belt 65 carrier, an endless belt for said carrier, means for driving said endless belt, said means comprising a drum, a gear carried by the drum, a worm arranged to engage said gear, means for imparting a vibratory movement to the belt carrier at right angles to the direction of the travel of the belt and in a plane parallel with the axis of the gear, said last named means comprising trunnions carried by the side of the belt, the axis of 75 the trunnions being parallel with the axis of the gear, means for slidably supporting the trunnions, a toggle joint having one end fixed and the other end secured to one of said trunnions, and means for operating the 80 toggle joint.

HARRY P. McINTIRE.
